UNITED STATES PATENT OFFICE.

RICHARD C. DRINKER, OF QUINCY, MASSACHUSETTS.

REMOVABLE PARTITION FOR METAL-HEATING FURNACES.

1,330,244.

Specification of Letters Patent. Patented Feb. 10, 1920.

Application filed October 3, 1919. Serial No. 328,163.

To all whom it may concern:

Be it known that I, RICHARD C. DRINKER, a citizen of the United States, residing at Quincy, county of Norfolk, and State of Massachusetts, have invented certain new and useful Improvements in Removable Partitions for Metal-Heating Furnaces, fully described and represented in the following specification and the accompanying drawings, forming a part of the same.

This invention relates to a partition which may be inserted removably in the heating-chamber of a metal heating-furnace to subdivide the space into convenient compartments which can be heated and used separately when the furnace is not wholly required for heating long articles.

Such partitions are shown in application No. 321,126 filed September 2, 1919 for patent on open side furnace; and the present invention relates to a particular construction for the partition by which it is provided with detachable foot-plates to support it upon runways when the partition is in use, and which may be stored separately and far more compactly by separation from the partition when it is not in use.

The invention includes various details of construction, which will be understood by reference to the annexed drawing, in which Figure 1 is an elevation of a furnace with two partitions therein dividing it into three separate spaces, the door in front of two such spaces being raised or elevated to expose the interior to view; Fig. 2 is a cross section of the furnace adjacent to a partition supported on foot-plates the door of the chamber being raised; Fig. 3 is a plan of the parts shown in Fig. 4 in section on line 3—3 in Fig. 1; Fig. 4 is a side elevation of the frame for one of the partitions mounted upon three detachable foot-plates; Fig. 5 is an end elevation of the parts shown in Fig. 4; Fig. 6 is a cross section of the frame of the partition taken on line 6—6 in Fig. 4; Fig. 7 is an inverted plan of the foot-plates shown beneath the partition-frame in Fig. 4; and Fig. 8 is an edge view of one of the foot-plates upon a larger scale than Fig. 4.

a designates the heating-chamber of a fur-

nace which is of much greater width than length. *b* designates the partitions mounted upright upon foot-plates which are supported upon rows of balls *d* guided in runways *e* 55 upon the floor.

The two partitions divide the heating-chamber *a* into three spaces which are provided with separate doors *f*, *f'* and *f''*.

The doors *f'* and *f''* are shown raised in Figs. 1 and 2.

A combustion-chamber *g* is shown beneath the heating-chamber in Fig. 2 but forms no part of the present invention, as it is immaterial to this invention how the heating-chamber is heated.

Each partition is formed of a cast-metal frame having a web *h* at the middle of its thickness with flanges *i* projecting squarely from the web to both sides of the partition. 70

The flanges cross the faces of the partition dividing it into various spaces in which the fire-brick or filler can be retained, which is essential to preserve the partition from destruction in the heating-chamber. 75

The web is formed with apertures *j* which connect the corresponding spaces upon opposite sides of the web, and permit fire-bricks or filler *k* to be extended through the apertures, as shown in Fig. 6, to lock together the refractory coating upon the opposite sides of the partition, by engagement with bricks *k'* which are laid directly against the web *h*.

When all the spaces are filled with bricks, 85 the partition is protected sufficiently for practical wear, as the web *h* which holds the frame in shape is not at any point exposed directly to the furnace heat.

A rib *l* is shown extended along the top 90 of the partition and projected closely to the roof *a'* of the furnace-chamber *a*, to obstruct the passage of the gases past the upper edge of the partition. A rib *l'* performs the same function upon the foot-plate.

A narrow rib is employed to facilitate the chipping off of the rib if necessary to make the partition fit approximately to the roof *a'*.

The partition is shown supported upon three foot-plates, consisting each of a metallic plate *m* having parallel ball-races *m'* 100 upon the under side to fit two rows of balls

n which are movable in runways *n'* upon the floor. Such runways extend transversely across the heating-chamber, and outside of the same far enough to draw the partition wholly from the chamber, when it can be removed and stored until needed for again dividing the chamber.

A longitudinal seat *o* is formed in the upper side of each foot-plate of suitable width to receive the bottom of the partition (see Fig. 5) and operating when a plurality of foot-plates is used to hold them all in line with the body of the partition. Such a fitting makes the foot-plate and partition completely detachable so that both can be stored independently, and the foot-plates can be fitted for again supporting the partition by simply placing three of them contiguous over the runways supported upon the balls therein. To prevent the passage of gases between the ends of the truck, a tongue *p* is formed upon one end of each and a notch *q* upon the opposite end, such tongues and notches interlocking when the foot-plates are placed in proximity.

It is understood that such trucks are adapted only to move in a straight line and to form a straight row when assembled, such as is shown in Fig. 7, adapted to receive and transport the partition *b*.

In the lower corners of the partition recesses *s* are shown with transverse pin *r* in each, and such pins are provided to engage the opposite ends of a chain or sling which would be hung from a crane and extended over the upper corners of the partition to such pin for lifting and moving the partition.

Holes *r'* are shown perforating the frame near the middle of the top which may be used for a similar purpose.

It is evident that a single foot-plate of suitable length could be used if constructed to receive and center the partition thereon the same as a plurality of foot-plates; but the plurality is preferable because it makes each part lighter for handling.

This is a material advantage, as such partitions are not in use all the time and take less room when stored if mounted detachably upon the foot-plates and if the foot-plates themselves are relatively small so as to be moved with facility.

By the construction shown, the entire foot-plate consists of a single casting having parallel ball-races upon its under side, and a suitable seat upon the upper side to receive and hold a partition.

A recess in the foot-plate to guide the setting of the partition thereon is shown in the drawing formed by ridges *o'* running along the edges of the foot-plate over the ball-races; but any other means may be employed to form a loose detachable engage-

ment between the partition and the foot-plate to guide the operator when setting the partition upon the truck.

Provision is also shown in Figs. 3 and 4 to prevent the passage of gases past the rear edge of the partition and serving at the same time to steady the partition and hold it upright.

This provision consists of a vertical groove or recess *u* formed in the rear wall of the furnace into which the rear edge of the partition is pushed when it is inserted in the heating-chamber, and which embraces its edges or corners with sufficient snugness to hold the partition steady and prevent the passage of gases.

A plurality of trucks is desirable to support the partition so as to permit of the expansion of this supporting member.

Such expansion is permitted by placing the trucks with an open clearance between their adjacent ends, and the passage of gases between the several trucks is prevented by the interengagement of the tongues *p* and notches *q* upon the adjacent ends of the trucks.

It will be readily understood that a foot-plate greater in width than the thickness of the partition is necessary to sustain it upon the balls in the runways *n'*, and if such foot-plate were integral with the partition it would prevent the piling of the partitions with their sides in close contact when not in use in the heating-chamber.

The foot-plate shown herein is not adapted for any other purpose except to support the partition while in use in the furnace, and is therefore different from ordinary trucks which may be used to carry miscellaneous articles.

The foot-plate shown herein is one of the elements which operates to entirely close the space between separate compartments of the furnace, and has the rib *v* projected from its lower side for the express purpose of preventing the passage of gas beneath the partition.

Having thus set forth the nature of the invention what is claimed herein is:

1. In a metal-heating furnace having runways extended transversely of the heating-chamber, foot-plates having ball-races corresponding to the runways and seats in alignment upon the tops of the foot-plate, and a partition fitted to the seats upon the runways and supported thereby in working position within the heating-chamber.

2. In a metal-heating furnace having runways extended transversely of the heating-chamber, a partition provided with a plurality of means for supporting it movably upon the runways such means having recesses in alignment with one another upon their upper sides adapted to receive and

center the partition and being detachable from the partition when removed from the heating-chamber for storage.

3. In a metal - heating furnace having 5 runways extended transversely of the heating-chamber, a partition provided with plurality of interlocking detachable foot-plates for supporting it movably upon the runways, such foot-plates having recesses in 10 alinement with one another upon the upper sides adapted to receive and center the partition, and ribs upon their under sides to prevent the passage of gases.

4. In a metal - heating furnace having 15 runways extended transversely of the heating-chamber, a partition provided with means for supporting it movably upon the runways and the rear wall of the furnace having a vertical recess adapted to receive 20 the rear edge of the partition when pushed thereinto and to then retain the partition in a vertical position.

5. A removable partition for a metal heating-furnace, comprising a frame having 25 a central web with flanges projected squarely therefrom at the edges and across

its flat sides, and apertures through the web between the crossed flanges for binding together the refractory material upon the opposite sides of the web.

6. A removable partition for a metal heating-furnace, comprising a frame having 30 a central web with flanges projected squarely therefrom at the edges and across its sides the frame's thickness correspond- 35 ing to the length of a fire-brick, apertures through the web between the crossed flanges, and fire-brick extended transversely through the apertures for binding together the refractory material upon the opposite sides of 40 the web.

7. A removable partition for a metal heating-furnace, comprising a recessed frame having its recesses filled with refractory material and sockets in the ends of the 45 frame with transverse pins fitted to engage means for lifting the frame from the truck when required.

In testimony whereof I have hereunto set my hand.

RICHARD C. DRINKER.
